US0D1054048S

(12) **United States Design Patent** (10) Patent No.: **US D1,054,048 S**
(45) Date of Patent: ** Dec. 10, 2024

(54) **FASCIA GUN**

(71) Applicant: **Linyun Zhuo**, Guangdong (CN)

(72) Inventor: **Linyun Zhuo**, Guangdong (CN)

(**) Term: **15 Years**

(21) Appl. No.: **29/887,904**

(22) Filed: **Mar. 26, 2023**

(51) LOC (14) Cl. **24-01**

(52) U.S. Cl.

USPC **D24/215**

Primary Examiner — Michael A Maharajh

(57) **CLAIM**

The ornamental design for a fascia gun, as shown and described.

DESCRIPTION

FIG. 1 is a perspective view of a fascia gun showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the figures are for the purpose of illustrating portions of the fascia gun, which form no part of the claimed design.

1 Claim, 8 Drawing Sheets
